STOP MOTION, ETC.

Adolph Wachsman, Brooklyn, N. Y., assignor to
Stop-Motion Devices Corporation, Brooklyn,
N. Y., a corporation of New York

Application July 13, 1935, Serial No. 31,234

10 Claims. (Cl. 66—163)

This invention relates to strand tension devices and more particularly to such devices when applied to textile machines, and more especially knitting machines, for the purpose of effecting the stopping of the machine and avoiding the breaking of a yarn or thread or needles. The mechanism or device hereinafter to be described in detail, is especially useful when applied to a multi-feed knitting machine where several threads or yarns are being simultaneously fed to the needles.

In the drawing:

Fig. 1 is a side elevational view of the thread tension mechanism, a thread engaging lever being shown in two parts and a portion of the cover of the casing within which some of the parts are housed being broken away more clearly to show the construction;

Fig. 2 is a front elevational view of the parts shown in Fig. 1;

Fig. 3 is a fragmentary view of the parts shown in Fig. 1 with the lever in a different position; and

Fig. 4 is a view of the under side of the housing showing a catch or detent which serves adjustably to tension a spring acting upon the lever.

Within the housing or casing 1 is mounted a metallic contact element 2 the latter being supported upon an end 3 of a lever 4 and being a part thereof. One arm of lever 4 is conveniently formed of wire bent into the desired shape. Specifically and as shown for purposes of illustration, that arm of lever 4 is bent into more or less U-shape as at 5, a grooved porcelain or other U-shaped eyelet 6 being retained in the bight of the end 5. The lever arm is turned at right angles as at 7 such right angled end being adapted to engage wall 8 of the casing 1 thus limiting its upward swinging movement.

From the right angled portion 7 the said arm is again bent at right angles as at 9, the extreme end 3 extending at right angles to the portion 9 and passing through a hole 10 provided in a wall 11 of the casing 1 and through a hole in the cover 12, the lever 4 thus being conveniently mounted for swinging movements in opposed walls of the casing 1. The contact 2 is made fast to the aforesaid arm of lever 4 to move therewith as by means of a set screw 13, the latter passing through a hole in the contact 2 and into clamping engagement with the end 3 of the lever arm. Depending from the contact 2 is the other arm of lever 4 consisting of a wire-like U-shaped element 14 one end of which is made fast to the contact 2 and the other end engag-

ing a coil of a spring 15, the other end of which spring passes through a hole in the lower wall 16 of the casing 1, a washer or other element 17 of a diameter or size greater than the diameter of the hole in the wall 16, serving to retain that end 5 of the spring 15. The tension of the spring may be conveniently varied by means of a pivoted catch or detent 18 which is pivotally mounted in the wall 16 as by means of a screw 19. To effect desired adjustments of the spring 15 the catch 18 or detent 18 is provided with a bent portion 20 which may be readily engaged to swing the catch to and from the spring engaging position, a notch or recess 21 permitting the catch to pass between convolutions of the coil spring 15 and retain the spring in any desired position of adjustment.

When operating as a stop motion the device is provided with a contact 22 including a screw 23 and nuts 24 the latter retaining the head of the screw 23 in clamping engagement with a leaf spring contact 25 between which and the upper wall 26 of the casing 1 is clamped on insulating washer 27 as of rubber. A second insulating rubber or other washer 28 is interposed between 15 the nuts 24 and the upper casing wall 26. The contact spring 25 is thus insulated from the metallic casing 1, the diameter of the shank of the screw 23 being smaller than the diameter of the hole in the wall 26 through which the shank 25 passes, and the shank being, preferably, surrounded by one of the washers 27, 28.

When the opposed face of contact 2 engages leaf 25 as shown in Fig. 3, an electric circuit (not shown) is closed which operates a stop motion as 35 usual in devices of this character, one side of the circuit being connected to the casing 1, as by the screw 19 or by means of a common return through the machine frame to which each casing 1 is connected at 28', there being a stop motion 40 mechanism associated with each feeding station. The other side of the circuit is connected to the leaf contact 25 as by means of a wire held between the nuts 24.

The parts just described are, preferably, in- 45 closed in the casing 1 as by means of the cover plate or wall 12, lugs 29 engaging correspondingly shaped notches 30 provided in the cover plate to seat the cover in position and prevent the same from turning. A screw 31 which passes 50 through a hole in the cover plate 12 and into threaded engagement with the wall 11 retains the cover plate 12 in position.

It is ordinarily advantageous to use a relatively long spring in connection with movable le- 55

vers such as 4 because of the fact that a slight elongation of a long spring does not greatly increase the tension whereas if a short spring were used the same elongation would greatly increase the tension. As it is desirable, especially when 5 knitting with some kinds of yarns, to enclose the contact points of an electric stop motion as herein disclosed, it is more convenient to use a relatively short spring such as 15 which can be 10 enclosed within a relatively small housing thus preventing lint, dust, etc., from impairing the effectiveness of the electrical connection between the contacting faces of the parts 2 and 25. By providing the slip or sliding connection 15 between the spring 15 and the arm 14, the disadvantages of using a short spring are overcome by permitting the spring quickly to decrease its pull upon the arm 14 at about the time or shortly after the stop motion is actuated by the 20 contacts 2, 25.

The operation of the mechanism hereinbefore described may be briefly summarized as follows: The stop motion actuator including the contact 25 2 which is pivotally mounted in the housing, is movable responsive to swinging movements imparted to the lever 4 as a result of varying yarn tensions, the spring 15 being movable along the arm 14 when or approximately when the member 2 temporarily arrests the movement of the strand 30 from its source of supply or effects the stopping of the machine by engagement with the spring contact 25 or otherwise. The first phase of the movement of the lever 4 from the position shown in Fig. 1 to that shown in Fig. 3 does not elongate the spring 15 to any extent but merely swings the spring slightly to the left, Fig. 1; in the second phase of the downward movement of the said 35 lever the spring is somewhat elongated thus increasing its pull upon the arm 14; at about the time the electrical contact is effected and the stop motion actuated the spring 15 slips to the position shown in Fig. 3 which quickly decreases the tension or pull exerted by the said spring upon the arm 14.

In winding cones the knots are usually located 45 at the top thereof but occasionally the knots are positioned somewhere intermediate the length of the cones in which case when a thread or yarn is drawn off the top of a cone on its way to the needles, a knot may engage the length of yarn 50 that is being drawn off the cone and prevent its free passage to the needles which will result in the breaking of the yarn usually at the needles or in the breaking or bending of a needle hook. It also occasionally happens that a length 55 of yarn catches underneath the cone and the free passage of the yarn to the needles is likewise impeded again resulting in damage to the needles or in yarn breaking. To avoid such 60 breaking of the yarn or damage to the needles, stop motion mechanisms of various types have been used on knitting machines such mechanisms embodying movable arms such as 4 which are moved by an increase in tension on the yarn and 65 when so moved effect the stopping of the machine before a yarn breaks or damage to the needles results. In the mechanism herein shown if a yarn does not pull freely from its cone the arm 4 will move downwardly and if the tension 70 on the yarn is not relieved, the stop motion will act and the machine will be stopped as hereinbefore described.

When excess tension is imposed upon a yarn for the reasons just stated, the arm 4 moves downwardly a short distance toward but not to the 75

position shown in Fig. 3, and if the yarn is not then relieved of the excess tension the arm 4 moves further downwardly such further movement being increasingly resisted by the elongation of the spring 15, such elongation of the said 5 spring being due to the upward movement of the arm 14. If the excess tension on the yarn is not then relieved the arm 4 continues its movement to or approximately to the position shown in Fig. 3, contact between the spring 25 and the element 2 10 then closing the circuit and stopping the machine at about the time the spring 15 slides along the arm 14 to the position shown in Fig. 3.

After the circuit is closed the machine does not stop for a half to three quarters of a revolution as of a needle cylinder during which time 15 yarn is being drawn from the source of supply, and to provide some yarn for the needles during this half or three quarters of a revolution the lever arm is permitted to move still further downward thus tending to create a slack in the yarn which is taken up by the needles. During this last phase of the movement of the lever arm the spring is in the position shown in Fig. 3, and in which position the said spring is not under the 25 same degree of tension as before; furthermore, the spring at that time engages the arm 14 at a point substantially in line with the point of attachment of the spring to the casing and the pivot of the contact member 2, the result being 30 that the spring exerts little pull tending to elevate the other arm of lever 4.

The screw 13 provides a convenient means for 35 adjusting the relative angular positions of the two arms of the lever 4 by circumferentially adjusting the lever arms with respect to the lever axis thus permitting a change in the timing of the movement of the spring 15 from the position shown in Fig. 1 to that shown in Fig. 3.

Although the invention has hereinbefore been 40 described as being applied to an electric stop motion, the member 25 may be replaced by a trip member acting upon a mechanical stop motion. Furthermore, and as hereinbefore mentioned, the tension mechanism including the lever 45 4, is not necessarily limited in its application to a stop motion.

A spring 15 has, for convenience, been shown, but equivalent means such as a weight or weights connected to the arm 14 may be substituted for 50 the spring.

The parts and combinations thereof have been hereinbefore specifically described without the intention, however, of limiting the invention otherwise than as called for by specific recitations in the claims themselves. 55

I claim:

1. A stop motion for use in textile machines including a movable arm adapted in one position to stop the machine, a spring connected to the arm to hold it in such a position as not to effect the stopping of the machine, movement of the arm in the direction to stop the machine acting to increase the force of the spring tending to resist such movement, and further movement 65 of the arm in the same direction reducing the effective force of the spring on the arm.

2. A stop motion for a knitting machine including a housing and contact members for closing an electric circuit mounted in the said housing, one of said contact members being movable with respect to the other, means for resisting movement of the movable contact member to a position to close the circuit, said means becoming increasingly effective as the contact mem- 75

ber moves in the direction to close the circuit, the tendency of said means to resist movement of the said contact member being substantially reduced when the movable contact member is in engagement with the other contact member.

5. A strand controlled stop motion mechanism adapted to stop movements of a strand from a source of supply and including a movable arm, the construction and operation being such that 10 when the arm is moved from one position to another position by the strand, movement of the strand from the source of supply is temporarily arrested, the arm when moving from the first mentioned position to the second mentioned position first encountering increased resistance to said movement, the resistance to the movement of the arm being substantially decreased when the stop motion is actuated.

6. A stop motion for a knitting machine including a movable member the movements of which are yarn controlled, the said member being moved to one position by excess tension on the yarn and when in said position acting to effect the stopping of the knitting of the yarn, means 20 acting upon the said member tending to retain it in a position where the stop motion is not effective, the construction and operation of the mechanism being such that when the member moves to the position to effect stopping of the machine the effective force of the said means acting in opposition to the said movement of the member is substantially decreased approximately when the stop motion is actuated.

7. A stop motion for a knitting machine including a closed housing within which are electrical contacts for effecting the stopping of the machine, one of such contacts being movable with respect to the other to close and open the electric circuit, a lever to which the contact first mentioned is connected, said lever being pivotally connected to the said housing one arm of the lever being positioned within the housing and the other arm thereof extending to the outside thereof, spring means at one end slidably connected to the arm first mentioned, the sliding of the spring along the arm acting to decrease the tension of the spring means upon the arm, the said spring means at the other end being connected to the housing, the lever arm second mentioned having an eyelet through which a yarn may pass, the said lever being movable upon its axis under the influence of the yarn passing through the said eyelet.

8. A yarn controlled stop motion lever and a support therefor, said lever being pivotally connected intermediate its ends to the said support to provide two lever arms, spring means connected to one of the said arms, said spring means being movable adjacent to the pivot point of 50 the lever as the said lever moves in one direction,

said arms being circumferentially adjustable with respect to the axis of the lever, and movable therealong, the relative adjustment of the two arms varying the effective force exerted by the spring upon the said one arm, the said spring means being adjustably mounted in the support, a support and an adjustable connection between the spring and the support.

9. A housing including walls enclosing the contained mechanism on all sides, contact members for an electric circuit enclosed in said housing, one of said contact members being movable with respect to the other to effect the closing of the circuit, spring means for normally keeping the circuit open, said spring means being also enclosed within the housing and being so connected to the movable contact member that when the movable contact member has moved to a position to close the circuit, the force of the spring tending to maintain the circuit open is decreased.

10. An electric stop motion for a knitting machine including a closed housing and contact members mounted therein to effect the closing of an electric circuit, a lever pivotally mounted in the said housing, one arm of the said lever extending outwardly of the housing and the other arm being contained within the housing, one of the said contact members being connected to the said lever and movable therewith, the movements of the lever being responsive to strand tension, adjustable spring means for acting upon the lever arm mounted within the housing normally to retain the other arm in non-circuit closing position, the said other arm being movable to another position in response to strand tension in opposition to the force exerted by the adjustable means acting upon the arm within the housing, the last mentioned movement of the said other arm being in opposition to the tension exerted by the said adjustable spring means and being substantially reduced as the circuit is closed.

11. A stop motion mechanism including a support, a movable arm and a spring connected at one end to the arm and at its other end to the support, said other end of the spring being adjustably connected to the support and means for effecting adjustment of the spring including a movable catch adapted to engage between convolutions of the spring to retain the same in adjusted position.

12. A stop motion including a housing, a lever pivotally mounted in the housing and a spring contained therein, one end of said spring being connected to the lever the other end of the spring passing through the housing, a catch mounted externally of the housing and adapted to engage and retain the spring in any one of several positions of adjustment to vary the tension exerted by the spring upon the lever.

ADOLPH WACHSMAN. 60
